LOOSE-LEAF BINDER

John Schade, Holyoke, Mass., assignor to National
Blank Book Company, Holyoke, Mass., a cor-
poration of Massachusetts

Application April 24, 1939, Serial No. 269,556

3 Claims. (Cl. 129—17)

This invention relates to an improved loose-leaf binder, particularly of the type used to hold loose-leaf sheets of the visible index bookkeeping kind. In such binders, the user, in addition to inserting new sheets, frequently wants to shift some of the visible index sheets longitudinally of the back to change, for instance, their chronological or alphabetical order. According to the present invention, the binder is constructed to provide for the utmost flexibility and simplicity of action for this purpose and at the same time has numerous novel features which render the structure more satisfactory and serviceable over a period of rough use such as these binders are subjected to.

The manner in which my structure has been arranged to accomplish the desired results can best be understood from a reading of the specification in connection with the accompanying drawings, in which:

Fig. 1 is a top plan view of the binder, with the covers opened and broken away to save drawing space, and showing the prong sets in one of several overlapped positions determined by a novel latch mechanism;

Fig. 2 is a sectional view on line 2—2 of Fig. 1;

Fig. 3 is a top plan view of a sufficient part of the right hand portion of Fig. 1 to show how the prong sets may be offset longitudinally an amount equal to the distance between a pair of binding holes in an index sheet;

Fig. 4 is a view of the parts of Fig. 3 but illustrating how these parts may be manipulated so that the prong sets are offset longitudinally twice the space between binding holes;

Fig. 5 is an enlarged sectional view on line 5—5 of Fig. 4 and shows details of part of the mechanism used to control the amount of longitudinal offset given the prong sets;

Figs. 6 to 8 are fragmentary top plan views of a portion of the structure of Fig. 1 showing the various overlapped positions to which the prong sets may move under control of a novel latch mechanism; and

Fig. 9 is a side elevation taken on line 9—9 of Fig. 2.

Referring first to Figs. 1, 2 and 9, the binder consists generally of a pair of Z shaped angular back plates 5 and 6, having their short depending legs 3 pivoted together by means of a piano hinge at 7. The long upstanding legs 8 and 9 terminate in a series of spaced hinge eyes 11 to which are pivoted covers 12 and 13 by means of hinging strips 14 and 15 which have hinge

eyes 16 that are complementary to hinge eyes 11 and pivotally connected thereto as indicated.

Secured to each of the long legs 8 and 9 of plates 5 and 6 by any suitable means is an anchor plate 17 and a hood member 18, this last to prevent the binder from scarring surfaces on which it may be used and to add a finished appearance. Each anchor plate 17 has a series of hook shaped tongues 20 which extend laterally from the top edge of the plates through the spaces between hinge eyes 11 to form a track for the prong carrying plates 21 and 22, see Fig. 2. As this last figure shows, plate 21 is a simple flat plate which lies parallel to the long leg 8 of plate 5 and carries a series of prongs 23 which extend in an arc over the plates 5 and 6 adjacent a similar set of prongs 24 carried by plate 22, which lies parallel to leg 9. However, plate 22 is angular in cross section with the short leg 25 of the angle overlying the flat surface of plate 6.

In the binder herein shown plate 21 is stationary, being secured to leg 8 in any suitable manner as for instance by spot welding, while plate 22 may slide longitudinally in the trackway formed by the tongues 20 of the right hand anchor plate 17.

As will be plain from the description thus far, the overlap of prongs 23 and 24 can be varied by pivoting the Z plates 5 and 6 around hinge 7 while their longitudinal position may be varied by sliding plate 22. Among the features of my invention are the novel means used to control these positions of the prongs to produce a new flexibility and positiveness of action not heretofore available.

As appears in Figs. 1 and 2, overlying short leg 25 of plate 22 and secured thereto is the short angular rack member 30 having its toothed portion extending downwardly through a slot 31 in plate 6. Rack member 30 has its teeth in engagement with pinion teeth 32 on pinion 33 pivoted at 34 to the bottom of plate 6. As is clear from Fig. 1, prong carrying plate 22 may be moved longitudinally to displace the prong set 24 by merely rotating pinion 33 about its pivot 34, the depending arm of the rack 30 by cooperation with slot 31 serving to guide one end of the lower edge of plate 22 and the other end of the lower edge being guided by clip 35 riveted as shown to plate 6.

In addition to the pinion teeth 32, pinion 33 has a set of gear teeth 38, see Fig. 1, which are formed on a larger radius than teeth 32. The extremities of these teeth 38 extend through a slot cut in the depending leg 3 of plate 6 and are

engaged by a series of slots 39 cut in the depending skirt of an angular slide 40 which overlies plate 6, see Figs. 1, 2 and 9, and may slide between limits thereon parallel to the axis of the central hinge 7.

At its forward end, slide 40 has a pair of downwardly directed tabs 41 struck out of the material of the slide, the tabs extending through a slot 42 cut in plate 6 with their extremities rebent to underlie the bottom surface of plate 6 and secure the forward end of slide 40 to said plate, see Fig. 3. Towards its lower end, slide 40 has secured to it a pin 43 extending through a slot 44 likewise cut in plate 6. As is shown in Fig. 5, this pin 43 has an enlarged head underlying plate 6 to maintain this end of the slide 40 in sliding contact with plate 6.

Comparing Figs. 1 and 4, it will be seen that slots 42 and 44 in plate 6 are dimensioned so that they act to limit the motion of slide 40 to the two extreme positions to which pinion 33 can be moved by cooperation of gear teeth 38 and slots 39 (see also Fig. 9). As will also be apparent from these figures, when the slide 40 passes from its normal position of Fig. 1 to its maximum displaced position of Fig. 4, the prongs 24 have been displaced longitudinally from prongs 23 a distance corresponding to twice the distance between adjacent binding holes in the binding sheets. To make this clear, note in Fig. 4 the distance between lines X and Z which shows the displacement of prong 24 from the position of Fig. 1, while the distance X—Y is the normal distance between binding holes in the index sheet.

While the mechanism just described provides for a longitudinal prong offset equal to twice the distance between binding holes in index sheets, I have found that normally an offset just equal to the distance between binding holes is the most likely to be used. I therefore have provided a specially constructed handle which not only serves as a convenient means to shift slide 40 but also is constructed so that it may be rocked to two different positions, in the first of which it limits the motion of slide 40 to half its normal or full stroke so that the longitudinal displacement of prongs 24 is only equal to the distance between binding holes, and in the second of which it allows for the full stroke of slide 40. Referring to Figs. 3 to 5 and 9, this handle consists of a flat angular member 50 having a vertical offset 50' at one end and pivoted as at 51 near the lower end of slide 40. A short leaf spring 52 is riveted to member 50 and holds a small ball bearing 53 which can pass freely through a hole 54 in member 50, into either of two seats 55 and 56 provided in slide 40, see Fig. 5. At the lower end, slide 40 likewise has a vertical stop 57 and a rebent keeper 58 formed integrally from the material of the slide as shown. This stop 57 and the keeper 58 limit the rotation of member 50 about pivot 51 to the two positions shown by Figs. 3 and 4, while the ball 53 acts as a spring pressed detent to maintain the member 50 in either position.

Member 50 has a nose 59 formed at its forward end and in the position of member 50 shown in Fig. 3 this nose overlies a slot 60 in slide 40. Extending upwardly through slot 60 is a tongue 61 struck up from plate 6. Therefore, if the handle 50 is left in the position of Fig. 1 and the slide 40 moved by grasping vertical offset 50', the nose 59 contacts the tongue 61 and the motion of the slide is limited to one-half the maximum, the prongs being displaced only the distance

X—Y, that is the space between successive binding holes, see Fig. 3.

From the above it is clear that the user is allowed a choice of the amount of longitudinal displacement to be given the prongs and can control the displacement by merely shifting the handle 50. This feature makes the binder extremely flexible for rapid use in shifting operations of more than one kind or distance and when combined with the latch mechanism about to be described and which controls the overlapped relation of the prong sets, results in various desirable binder manipulations being possible and more conveniently than heretofore.

Referring now to Figs. 1, 5 and 9, plates 5 and 6 are notched midway between their ends as at 70 and 71 to provide for a pair of latch members 72 and 73 having gooseneck extensions of the same curvature. As is indicated, member 72 is fixedly attached to the bottom of plate 5 and has its gooseneck portion extending through slots 70 and 71 and underlying plate 6, see Fig. 1. Latch member 73 is, on the other hand, pivotally connected as at 74 to the bottom of plate 6 and has its gooseneck portion extending to and underlying plate 5. Along one edge, member 73 has a nose or dog 75 which can engage a series of shoulders 76, 77, 78, formed as serrations along the adjacent edge of member 72 to allow the plates 5 and 6 to be separated different amounts and thereby vary the overlap of the prongs 23 and 24. On the opposite edge, member 73 has a pair of cam surfaces 79 and 80 which are constructed to cooperate with the top edge 81 of slot 70 and act as an escapement in a manner to be described. To rotate member 73 and thereby release the latch mechanism, a trigger rod 85 is provided which is in the form of a long flat bar with oppositely disposed offset ends 86 and 87, and which is positioned to be parallel and inside of the depending leg 3 of plate 6, see Figs. 1 and 5. Trigger rod 85 is dimensioned so that the offset 87 lies beyond the lower end of the binder to form a convenient handle. Offset 86 protrudes through a slot cut in the depending leg 3 of plate 6, see Fig. 9, and forms a support for that end of the trigger. Where the trigger rod underlies latch member 73, it has an upstanding integral lug 88 which passes through a hole in member 73. A spring 89 (see Figs. 5 and 9) is tensioned about depending lugs 90 and 91 on plate 6 and has its end engaging a shoulder 92 on trigger rod 85, the spring being wound to force the trigger member 85 in a direction to engage members 72 and 73. Thus the user may disengage latch member 73 from member 72 by simply pressing on offset 87, the upper end of notch 71 in plate 6 being provided with a slot 93 located on the depending leg 3 to allow for the motion of member 73, see Fig. 9.

Referring now to Figs. 1 and 6 to 8, I will explain in detail how the latch mechanism operates and what the function of cam surfaces 79 and 80 is. In Fig. 1, the book is in the position to which it will fall due to its own weight when the covers are opened. Usually this position is inconvenient for writing, as it is difficult to get at the sheets near their binding edges. The user may then push offset 87 (see Fig. 1) sufficiently to lift nose 75 clear of shoulder 76 and then release the pressure. As the two plates start to separate under their own weight, cam 79 hits the top edge 81 of slot 70 and aids the spring 89 (see Fig. 1) in forcing nose 75 downwardly in a direction to strike shoulder 77 and the separation

stops with the prongs overlapped as in Fig. 6, the prong sets 23 and 24 each having moved the distance from A to B. Then if it is desired to still further decrease the overlap, offset 87 is again pushed and when nose 75 clears shoulder 71, cam 80 forces the nose in a direction to abut shoulder 78 as shown in Fig. 7, the prongs moving from B to C. If the offset is again pushed to release the latch the prongs will open to the position shown by Fig. 8 where the various leaves on the prongs will be nearly flat and new ones can easily be inserted.

In this final position of Fig. 8, the curved edge 96 of member 13 in front of nose 75 contacts a similar edge 97 of member 12. Then all that is necessary to close the book is to manually rotate the plates 5 and 6 towards each other around hinge 7, the edge 96 of member 13 sliding over the various shoulders 78, 77 and 76 of member 12.

It is to be noted that in describing the above operation it has been stated that the offset 87 is "pushed and released" because the shape of cam surfaces 79 and 80 is such that while they force the nose 75 in a direction to contact the various shoulders, they are effective only part of the way, that is they stop contacting the top edge 81 while the nose 75 and shoulder 76, 77 or 78 are still slightly separated. Therefore, if the offset 87 were held inward, the plates 5 and 6 would pass at once to the wide open position of Fig. 8.

Thus, in effect, these surfaces 79 and 80 aid the spring 89 in bringing the nose 75 into contact with shoulders 77 and 78 and act like an escapement to assist the spring 89 in forcing the latch mechanism to act correctly. It is, of course, evident that the particular latch mechanism shown can be varied in many ways by those skilled in the art, once its principles are understood and I do not therefore wish to limit myself to the exact form shown, that being merely a preferred embodiment. For instance, if it is found desirable to make the escapement effective to positively force the nose 75 into engagement with shoulders 77 and 78, all that is necessary is to change the shape of cam surfaces 79 and 80 so that they bear on the top edge 81 until the nose 75 contacts the shoulders 77 and 78. Such a structure will not, however, be as flexible as the preferred form because in changing the overlap of the prongs from the position shown in Fig. 1 to that of Fig. 8, the offset 87 will have to be depressed three times.

The flexibility of this binder can now be understood because as it will be remembered, the offset relation of the prongs can be varied at any time independently of the overlapped relation and the amount of variation which is produced can be varied. Therefore, assuming that the binder is positioned with the plates as shown in Fig. 6 which is the normal writing position as previously explained, if the book is not too full of index sheets the prong sets 23 and 24 may clear the binding holes in these sheets which are impaled on each other's prongs and whatever offsetting or varying or chronological order is desired can be done in this position.

If the book is full, it is a simple matter to touch the offset 87 to open the book to the position of Fig. 7 and the prongs 23 and 24 will just barely overlap allowing for index shifting with a maximum number of bound sheets.

On the other hand, the book can be opened to the position of Fig. 8 from any other position, i. e., the position of Figs. 1, 6 and 7, by simply pressing on offset 87 and not releasing the pressure and this independently of the offset relation of the prongs.

It is, of course, clear that the number of shoulders 76, 77 and 78 on fixed latch member 72, as well as their position, can be varied to provide for different angular positions of plates 5 and 6, and that the escapement means provided by cam surfaces 79 and 80 can be made effective in case the number of notches is increased by providing suitable additional cam surfaces.

20 It will be seen from the foregoing that I have produced a binder for the purpose described which, though considerably involved in mechanical details, has been so arranged that its operation from the standpoint of the user is much simpler and allows more rapid work.

What I claim is:

1. A binder having a back portion including two hingedly connected plates, a set of prongs supported at the side edge of each plate, latching mechanism for controlling the angular relation of the hingedly connected plates and consisting of a fixed latch member on one plate having a series of notches along one edge, a pivoted latch member on the other plate having a dog adapted to engage said notches in said fixed latch member, a spring-pressed operating member adapted to releasably hold said pivoted latch member engaged with said fixed latch member, and additional means on said pivoted latch member to cooperate with one of said plates and force the pivoted member towards engagement with the fixed member when passing from one notch to another.

2. The structure of claim 1 with said last-named means consisting of cam surfaces on said pivoted latch member cooperating with one of said plates for the purpose described.

3. A binder having a back portion including two hingedly connected plates, a set of prongs supported at the side edge of each plate, latching mechanism for controlling the angular relation of the hingedly connected plates and consisting of a fixed latch member on one plate having a flat gooseneck portion with a series of notches along one edge, a pivoted latch member on the other plate having a flat gooseneck portion of the same curvature as said first-mentioned gooseneck portion, and having a dog adapted to engage said notches in said fixed latch member, a spring-pressed operating member adapted to releasably hold said pivoted latch member engaged with said fixed latch member, and additional means on said pivoted latch member to cooperate with one of said plates and force the pivoted member into engagement with the fixed member when passing from one notch to another.

JOHN SCHADE.
